UNITED STATES PATENT OFFICE.

GRANT LINES, OF FORT SMITH, ARKANSAS, ASSIGNOR OF ONE-THIRD TO ANDERSON B. MCKINNEY, OF FORT SMITH, ARKANSAS.

SANDWICH-TOASTING APPARATUS.

Application filed February 26, 1927. Serial No. 171,245.

This invention relates to a sandwich toasting apparatus and more particularly to an apparatus for simultaneously toasting the outer faces of slices of bread while in the 5 form of a sandwich.

An important object of the invention is to provide a device of this character which may be operated by gas burners which have been found to be more economical and reliable in service than electrical devices for 10 this purpose.

A further object of the invention is to produce a construction having two hot plates, one of which is pivoted and with 15 each of which burners are associated, the constructions being such that the manifold pipe conducting gas to the burners of one of the plates, serves as a hinge about which the plate may be swung to open position to 20 permit the sandwich to be placed in or removed from the toaster.

A further object of the invention is to provide a device of this character which may be relatively cheaply constructed, which will 25 be durable and efficient in service and a general improvement in the art.

These and other objects I attain by the construction shown in the accompanying drawings, wherein for the purpose of illustration is shown a preferred embodiment of 30 my invention and wherein:—

Figure 1 is a plan view of a toasting apparatus constructed in accordance with my invention;

Figure 2 is a section on the line 2—2 of Figure 1;

Figure 3 is a section on the line 3—3 of Figure 1;

Figure 4 is a section on the line 4—4 of Figure 1.

Referring now particularly to the drawings, the invention generally comprises upper and lower plates 10 and 11, maintained in spaced relation, as hereinafter 45 more fully set forth, and each having associated therewith a plurality of gas burners 12. With the gas burners of the upper and lower plates are associated manifolds 13 and 14, by means of which gas is conducted to 50 the burners 12 from a feed connection 15. The manifold 13 has a swivel connection 16 with the feed connection 15, of such character that this manifold may serve as a support for the plate 10 and at the same time 55 act as a hinge to permit the plate to be

swung from a position where it parallels the plate 10 to a position where it is perpendicularly related thereto. The feed connection 15 includes valves 17 for controlling the supply of gas to the manifolds 13 and 14. The manifold 14 is rigid both to the feed connection and to the plate 11.

The plate 10 is covered by a hood 18 secured thereto and having a lining of asbestos, as indicated at 19, on its under surface. 65 The side walls of this hood are provided with perforations 20 to permit the escape of products of combustion. Associated with the lower plate 11 are supporting legs or standards 21 sheathed about with metal 22 70 to provide a compartment 23 within which the burners 12 associated with the lower plate are arranged.

The feed connection, as hereinbefore stated, is rigidly connected to the manifold 75 14 and this feed connection is itself rigid. Associated with the valve 17 is a short nipple 24, which projects through the hood 18 adjacent one edge of the plate. This nipple has secured therein, by means of a 80 bushing ring 25, a tube 26, which projects into and rotatably fits within a ring 27 carried by the adjacent end of the manifold 13. Slidable upon the tube 26 is an asbestos packing ring 28, which abuts the end of 85 the manifold 13. Between the bushing 25 and this washer, a spring 29 surrounds the tube 26, a metallic washer 30 being interposed between the end of the spring and the asbestos washer. The adjacent ends of 90 the nipple 24 and manifold 13 are connected with one another by a threaded sleeve 31, which preferably has a tight screw joint with the nipple 24 at 32 and a long, threaded, 95 slightly loose joint with the manifold at 33.

It will be obvious that the manifold 13 may be rotated with relation to the nipple 24, without effecting the seal against the escape of gas and it will also be obvious that the connection provided will hold the 100 manifold 13 in axial relation to the nipple 24 during such rotation. This manifold, the burners of which are attached to the plate 10, as at 34, provides the actual pivotal support for this plate. To prevent undue strain on the edge of the plate remote from that through which the nipple 24 is extended, the plate is preferably provided with a lug 35 rotatably engaged in an eye 36 formed in the plate 37 secured to the metallic casing 22 110

associated with the lower burner plate. In order to support the burner plates in spaced relation when in the closed position at the edges thereof remote from those at which the manifolds are disposed, one of these plates has threaded therein a stop member 38, which engages the other plate to maintain the spacing. The free edge of the movable plate is provided with a suitable handle 39, by means of which it may be swung to open and closed position.

Since the construction hereinbefore set forth is capable of a certain range of change and modification without materially departing from the spirit of the invention, I do not limit myself to such specific structure except as hereinafter claimed.

I claim:—

1. A sandwich toaster comprising a pair of plates, gas burners for heating said plates, manifolds for the burners of each plate arranged at corresponding edges of said plates and a single gas feed connection for said manifolds maintaining said plates in spaced relation at said sides while permitting pivotal movement of one of said plates with relation to the other thereof.

2. A sandwich toaster comprising a pair of plates, gas burners for heating said plates, manifolds for the burners of each plate arranged at corresponding edges of said plates and a single gas feed connection for said manifolds, one of said manifolds being rigidly connected to said gas feed connection, the other of the manifolds having a swivel connection with the gas feed connection permitting pivotal movement thereof from a position where it parallels the first named plate to a position where it is perpendicular thereto.

3. In a sandwich toaster, a single rigid gas feed connection, a pair of parallel manifolds connected therewith, one of said manifolds

being rigid to the gas feed connection, the other of said manifolds being rotatable upon its axis, burners secured to and supported from each manifold, a plate secured to each burner and each having one edge thereof adjacent the manifold and means carried by one of said plates and engaging the other thereof for limiting movement of the opposite edges of the plates toward one another, the plate secured to the burners of the last named manifold having a hood attached thereto enclosing said manifold and burners.

4. In a sandwich toaster, a single rigid gas feed connection, a pair of parallel manifolds connected therewith, one of said manifolds being rigid to the gas feed connection, the other of said manifolds having a swivel connection with the gas feed connection permitting its rotation upon its axis, burners secured to and supplied from each manifold, a plate secured to each burner and each having one edge thereof adjacent the manifold and means carried by one of said plates and engaging the other thereof for limiting movement of the opposite edges of the plates toward one another.

5. In a device of the type described, as a sub-combination, means for connecting a swinging hot plate to a rigid gas feed connection comprising a manifold rigid to the plate, a tube of less size than said manifold or the gas feed connection, bushed to said gas feed connection and rotatably engaged in a bushing carried by the manifold, a compressible washer surrounding said tube and abutting the manifold, a spring likewise surrounding the tube and urging the washer toward the manifold and a coupling connecting said gas feed and manifold permitting rotation of the manifold.

In testimony whereof I hereunto affix my signature.
